(57) **CLAIM**

The ornamental design for a beer bottle holder, as shown and described.

DESCRIPTION

FIG. 1 is a top perspective view of a beer bottle holder;
FIG. 2 is a bottom perspective view of the beer bottle holder;
FIG. 3 is a top plan view of the beer bottle holder;
FIG. 4 is a bottom plan view of the beer bottle holder;
FIG. 5 is a right side view of the beer bottle holder;
FIG. 6 is a left side view of the beer bottle holder;
FIG. 7 is a rear view of the beer bottle holder; and,
FIG. 8 is a front view of the beer bottle holder.

The broken line showing is included for the purpose of illustrating portions of the article that form no part of the claimed design.
